CLAIM

The ornamental design for a digital multimeter including a jacket, as shown and described.

DESCRIPTION

FIG. 1 is a front view of a digital multimeter including a jacket.

FIG. 2 is a top view thereof.

FIG. 3 is a left side view thereof.

FIG. 4 is a right side view thereof.

FIG. 5 is a bottom view thereof.

FIG. 6 is a back view thereof.

FIG. 7 is a first perspective view thereof; and,

FIG. 8 is a second perspective view thereof.

The broken line(s) that define the bounds of the digital multimeter including a jacket and/or disclose the environment related to the digital multimeter including a jacket form no part of the claimed design.
